UNITED STATES PATENT OFFICE

LOUIS H. MORIN, OF NEW YORK, N. Y., ASSIGNOR, BY MESNE ASSIGNMENTS, TO
DOEHLER VENDING MACHINES, INC., A CORPORATION OF NEW YORK

TOILET-ROLL HOLDER

Application filed November 18, 1926. Serial No. 149,095.

The object of the present invention is to provide an improved toilet paper roll holder of that type in which the roll, when once applied to the device, cannot be removed. A stop is commonly provided whereby the rotation of the roll, when a sheet of paper is pulled, is limited to permit detachment of one sheet only at a time. With devices of this kind heretofore commonly in use, it is difficult and inconvenient to remove the empty roll carrier from its supporting bracket; also difficulty is often experienced in refilling the roll carrier and replacing it on the bracket. The invention overcomes these objections and provides novel means for securing the rotative element of the holder to its supporting member and for releasing the same.

The invention will be described with reference to the accompanying drawings, showing one embodiment thereof, and thereafter the invention will be pointed out in claim.

In the drawings:

Figure 1 is a plan view partly in section, a roll of paper being indicated by broken lines; Figure 2 is a front view of the device in operative position, and

Figure 3 is a fragmentary section on the line 3—3, Figure 2, with the holding means released.

The device comprises a base 1 having spaced forwardly projecting arms 2, which arms at their ends are formed with sockets 8, 8*. The base member thus described has formed therein spaced apertures *a* by means of which it may be attached to a wall.

The rotative element is formed of two spaced bars 4, which bars are connected by oval end pieces 4*, 4** and an intermediate connecting web or cross bar 5. End member 4* is formed with a lateral extension 6 which overhangs the adjacent arm 2 and provides a stop against rotation of the rotative roll supporting element except to a limited extent. This rotatable element forms a roll carrier which constitutes a roll-receiving core frame.

At its left hand end, the rotative element is provided with a projecting pivot stud 3 adapted to enter the socket 8 formed in the left hand arm 2. Mounted intermediate connecting members 4* and 5 and adapted for

endwise movement in apertures formed therein is a pivot rod 7, the construction of which is illustrated in detail, Figure 3. The rod is normally pressed to the right so that its end enters the socket 8* formed in the right hand supporting arm 2, a spring 9 being employed for such purpose. The spring at one end acts against a washer 10 secured to rod 7 and at its opposite end acts against the side of connecting web 5.

At the left hand side of connecting web 5 is a cam 9* which is adapted to act upon an adjacent angular extension 7* of rod 7 when said extension is moved upwardly, the action of the cam being to force rod 7 to the left and withdraw its end from socket 8* to permit withdrawal of the rotative element from its support.

It is intended that a roll having an oval center be placed upon the roll carrier or holding member, and when this is done the opening of the roll adjacent connecting member 4* will be closed by said member, and it will be impossible to manipulate rod 7 so as to release the roll, until the paper is depleted and the usual cardboard core, if employed, is removed to expose the angular extension 7* of the rod.

This extension projects beyond the cam 9* to form a handle. When the extension 7* is raised it will ride up the edge of the cam 9* with the result that the rod will be withdrawn from the socket 8*. When the extension 7* is lifted into engagement with the straight or flat portion of the cam rise, as shown in Figure 3 and indicated by the broken line circle in Figure 2, the cam 9* will retain the rod or journal pin 7 in its withdrawn position, to permit the quick and easy removal of the empty roll carrier.

After the roll carrier has been removed, for placing a roll thereon, the handle 7* is returned to the position shown in Figure 2, with the outer end of the rod 7 projecting from the end piece 4*. The cam 9* and spring 9 then cooperate to maintain the projecting end of the handle 7* out of the path of the roll, so as not to obstruct the latter as it is slipped over the roll carrier; and likewise so that the end of the handle 7* cannot catch

upon the inside of the roll and thus interfere with the inward movement of the rod 7 as its journal end is snapped into the bearing socket 8^x through the flaring guide groove shown in the inner side of the outer end of the arm 2:

In use, after a sheet of paper has been detached, gravity will return the partly rotatable roll holder to the position shown in the drawings, by reason of the aligned pivot stud 3 and releasable pivot rod 7 being off center relatively to the longitudinal members 10. In this position the handle 7^x is in convenient position for manipulation.

15 The face of the cam may bear a legend indicating that the extension 7^x is to be raised, as for example "Lift up pin".

It will be noted from the drawings that the cam 9^x has a uniform gradual spiral 20 cam rise terminating in a flat top which ends at the adjacent side bar 4 of the roll-receiving core frame or roll carrier, so that thus this frame bar forms a stop shoulder for the handle lever 7^x when the latter is swung 25 outward to its projecting position in withdrawing the projection pivot end of the rod 7. It will also be noted that the cam 9^x cooperates with the spring 9 to hold the handle lever 7^x at its normal non-projecting position 30 within the limits or confines of the roll-carrying core frame.

It is obvious that various modifications may be made in the construction shown in the drawings and above particularly described, within the principle and scope of the invention as defined in the appended claim.

I claim:

In a roll holder, the combination of a roll-receiving core frame of flattened transverse 40 shape including substantially oval end pieces provided with aligned eccentric pivots adjacent their upper ends, a rod rotatably and slidably mounted in the frame to form one of the said pivots, a spring for causing the 45 outer end of the rod to project to form a pivot which may be withdrawn against the force of the spring, a handle lever fixed on and projecting at an angle from the inner end of the pivot rod normally to extend 50 downward within the limits of the transverse bounds of the flattened core frame and substantially in the plane thereof, a cam on the core frame having a gradual spiral cam rise terminating in a flat top, a stop shoulder 55 for the handle lever formed on the core frame at the end of the flat top of the cam rise, the said cam being disposed and arranged to be engaged by the handle lever when the latter is swung outward along the cam rise 60 to a projecting position on the flat top of the cam adjacent the said stop shoulder thereby to withdraw the projecting pivot end of the rod and the said cam being also disposed and arranged to cooperate with the 65 spring for holding the said handle at its nor-

mal non-projecting position within the confines of the roll-receiving core frame, the said roll-receiving core frame further including a pair of spaced side bars which connect together the ends of the said end pieces and the upper one of which side bars forms the said stop shoulder for the handle lever at the end of the flat top of the cam rise, and a cross bar connecting together the side bars between the end pieces and on the side 70 of which adjacent to the handle lever the said cam is provided.

In witness whereof, I hereunto subscribe my signature.

LOUIS H. MORIN.
